DESIGN FOR A HEATING STOVE

Wilbur Henry Adams, Cleveland Heights, and John Alger Dahlstrom, Bay Village, Ohio, assignors to Perfection Stove Company, Cleveland, Ohio, a corporation of Ohio

Application July 29, 1936, Serial No. 64,110

Term of patent 14 years

To all whom it may concern:

Be it known that we, (1) Wilbur Henry Adams and (2) John Alger Dahlstrom, citizens of the United States, residing at (1) Cleveland Heights, (2) Bay Village, in the county of Cuyahoga and State of Ohio, have invented a new, original, and ornamental Design for Heating Stoves of which the following is a specification, reference being had to the accompanying drawing, forming part thereof, and wherein Fig. 1 is a front elevation of a heating stove showing our new design; Fig. 2 is a right hand side elevation thereof, and Fig. 3 is a plan view.

The dominant features of our design reside in the portions shown in solid lines.

We claim:

The ornamental design for a heating stove as shown and described.
